TOY LOGGING TRUCK

Robert E. De Graw, 13811 116th Ave. NE,
Kirkland, Wash. 98033

Filed Nov. 27, 1972, Ser. No. 309,782

Term of patent 14 years

Int. Cl. D21—01

U.S. Cl. D34—15 AJ

FIG. 1

FIG. 2

FIG. 3

FIG. 4

FIG. 6

FIG. 5

FIG. 7

FIG. 1 is a left side elevational view of a toy logging truck showing my new design, the right side being a mirror image thereto;

FIG. 2 is a top plan view thereof;

FIG. 3 is a bottom plan view thereof;

FIG. 4 is a rear elevational view of the tractor, the trailer having been omitted for convenience of illustration;

FIG. 5 is a rear elevational view of the trailer, the tractor having been omitted for convenience of illustration;

FIG. 6 is a front elevational view thereof;

FIG. 7 is a front elevational view of the trailer, the

tractor having been omitted for convenience of illustration.

I claim:

The ornamental design for a toy logging truck, as shown and described.
